UNITED STATES PATENT OFFICE.

BENJAMIN L. FRY, OF ST. LOUIS, MISSOURI, ASSIGNOR TO NATIONAL SALES MACHINE COMPANY, OF ST. LOUIS, MISSOURI, A CORPORATION OF MISSOURI.

COIN-CONTROLLING DEVICE.

Application filed September 17, 1926. Serial No. 136,173.

This invention relates to a coin controlling device having a small number of parts to effect a large number of different functional operations. The usual counterfeit tokens commonly employed to fraudulently operate various coin controlling machines are round disks of metal of a size approximating the slot in the apparatus, and either of iron, copper, or brass, which is commonly easily found either as waste in the form of metal punchings from factories, or bought cheap, as iron, copper, or brass washers, or round imperforate slugs of a size suitable to enter a slot machine. My invention resides in so designing the apparatus as to reject any of these cheap or waste products which might be readily available for dishonest use, by selective mechanism which will prevent them from going into a receptacle intended only to receive a proper coin. I effect this result by combined means which casts off all coins or disks made of magnetic material and also all washers regardless of what materials they are made, and in addition, all coins, disks, or washers being smaller in diameter than that of the proper coin, permitting only legitimate coins of proper dimensions to be delivered to the desired receptacle. For example, one of these selective influences is a permanent magnet so located, in accordance with one of my prior applications, as to deflect a coin of magnetic character with certainty, and prevent the same from traveling in the path designed for legitimate coins.

Another feature of my invention involves checking the speed of a coin as it passes along the coin chute and providing means by which it will be tilted by gravity by reason of an inclination of the coin chute away from the vertical plane.

A third feature consists in ejecting through another lateral gate all washers regardless of what kind of materials they are made, most of which are a standard product and easily accessible on the market. To accomplish this I provide a rotatable toothed sprocket wheel with its radial teeth in the plane of the coin channel, by which a washer is caught by a tooth through its central opening and by reason of the momentum of the washer rotates the wheel and tosses the washer through an opening in the side of the apparatus. With a legitimate coin, however, the sprocket teeth have no further

effect than to lift the legitimate coin, whose momentum sweeps it along and in an independent path of the coin channel to drop finally into a proper coin receptacle.

My invention, therefore, consists of a coin controlling device embodying a plurality of ejecting instrumentalities to prevent improper slugs or disks of metal of the same or less diameter, whether perforated or plain, from passing into the legitimate coin chute.

The several features of the invention will be more particularly described in the accompanying specification and the claims definitely indicated in the appended claims.

In the accompanying drawings which illustrate the invention:

Figure 1 is an elevation of the machine embodying my improvements.

Figure 2 is a view with the front removed to illustrate the coin chute and its action on a coin under varying conditions.

Figure 3 is an end elevation showing the manner I prefer to use in mounting my device.

Figure 4 is a sectional view on the plane 4-4 of Figure 2.

Figure 5 is a sectional view on the plane 5-5 of Figure 1.

Figure 6 is a similar view of Figure 5 under varying conditions.

Figure 7 is a sectional view in a horizontal plane on the line 7-7 of Figure 1.

Figures 8 and 9 are similar detached views under varying conditions.

Figure 10 is an elevation of a modified form.

Figure 11 is an edge view of the same.

Figure 12 is a view of Figure 10 with cover removed.

Figure 13 is a sectional longitudinal view of Figure 10 on plane 13-13 showing discharge magnetic material.

Figure 14 is a sectional view on plane 14-14 of Figure 10, showing discharge of a small coin.

Figure 15 is a transverse sectional view on plane 15-15 showing discharge of a washer.

Figure 16 is a sectional view on plane 16-16 of Figure 10 showing the sprocket 105 engaging a washer.

Figure 17 is a sectional view on plane 17-17 of Figure 10 showing washer or coin delivered in separate channels.

Referring now in particular to the draw- 110

ings, the frame of the apparatus is composed of a plurality of flat angular sections. The coin chute is formed of a metal casting 1 with a longitudinal recess capable of permitting transit of coins, and two superposed plates 2 and 3 latched and secured together by set screws 4, 5. This central member 1 is of thicker section than the side sections and is routed out with a longitudinal recess 6 to provide a coin chute and abutments to act as spacers for the side plate 3, with an integral projecting wedge-shaped lug 6 to lock in position a horseshoe permanent magnet 7 when spanned by the abutment and 10 in alignment with a lug 8 against which one pole of the magnet abuts. At the top of the member is a rightangled projection 9 integral with it, which permits the coin controlled device to be mounted securely by 15 screws, clamps, or otherwise, in a tilting or inclined position, as shown in Figure 3. When the channeled member and side plates are united by the set screws referred to there is a continuous coin chute for legitimate coins through from the top to the bottom. In the lower portion of the apparatus is rotatably mounted a toothed wheel sprocket 10 or a rotative toothed sprocket mounted on a pivot. This is supported in a 20 hood 11 having a rightangled base 12 to accommodate set screws to fit it to the member 3, and thus the support of the rotative ejector being carried under the hood 11. Certain parts of the coin channel walls are 25 routed out to promote easy transit of the coin. For instance, the walls are tapered to permit easy discharge of a bogus coin as indicated at 13, 13^a, or a deflecting action to effect a selective action as at 15 in Figure 9, 30 and at 15^a in Figure 8, and 24 in Figure 5, all of which sloping walls have an important function in assisting discharge of a bogus coin or in promoting a selective action to lead a good or bogus coin in different paths. 35 In the case of the sprocket tooth wheel the teeth are the positive selective factor, but the shape of the edges adjacent facilitate an easier coin travel and thus aid functioning. In the case of an undersized coin the provision 40 of the beveled edge 24 together with the tilt of the chute promote ejection and the coin dwells on the slope 24, rocks it outward and discharges. It will be noted from the drawings that Figure 5 shows a clear 45 opening for ejection of the undersized coin and, as this is on the opposite wall from the illustrated travel of Figure 2, some confusion may arise. However, in Figure 1 the side containing the ejection opening shows the coin in full lines as distinguished from the dotted position in Figure 2. 50 The magnet 7 which influences a magnetic counterfeit slug is fixed in such a position that only its lower pole approximates the 55 path of a coin introduced through a slot at the top of the chute. The magnet is fixed in position over a wedge-shaped support 18 and when assembled is firmly locked against movement with its upper limb bearing against a non-magnetic wall which diverts 70 a magnetic coin from contact with the upper pole; therefore, in falling through the chute the coin approximates a sloping edge of the lower pole and if magnetic is drawn thereto so it will slide or roll along the 75 under side until it approaches the neutral point of the magnet which will be at a point below a vertical wall, and the magnetic pull at this point would be insufficient to overcome the weight of the slug, in which case 80 it will drop and be discharged. As shown in Figure 2 the path of a magnetic slug 19 is shown under deflection in dotted positions, in position to be discharged from the chute; the several discharge openings are numbered 85 with an exponent. Such discharge is indicated in enlarged section in Figure 4. If, however, an undersized coin is introduced in the entrance of the coin chute it will be uninfluenced by the magnet and will drop 90 vertically as indicated by the dotted circle 20 and will rebound to the rear wall of the chute and be diverted and checked in speed, when it will roll slowly on a sloping wall on a tilted plane, as indicated in Figure 3, thus 95 causing it to lean outward as indicated in Figure 5 and be discharged as indicated in dotted lines in Figure 5. When a legitimate coin is introduced into the coin chute it will traverse the chute through its several 100 angles until reaching the sprocket tooth wheel 10, when it will be diverted by the tooth of the sprocket as indicated at 15 to the legitimate coin path of discharge. Now if a non-magnetic washer is introduced into 105 the coin chute it will traverse the same until reaching the sprocket tooth wheel when it will be engaged by a tooth of the same, as shown in Figures 7 and 8, and under its 110 gravitating influence will tilt the sprocket and carry it forward, as indicated in Figure 8, into an independent path where it will be discharged. 115 Referring now to Figures 10 to 17, similar parts in this modification are numbered 120 correspondingly to similar parts in the figures hereinbefore described. As seen, the permanent magnet 7^a is fixed in an inclined position with the neutral point lowermost and with its one pole in the path of a dropping coin, similarly to the action already 125 described. This magnet is locked by a lug 32 spanning its poles and secured by a washer 31. In all the figures I have lettered the bogus coins and the legitimate coins and the undersized coins by numerals, and I have correspondingly numbered the discharge passages of the different magnetic and non-magnetic coins, washers and disks. 130 The different metallic disks constituting 135

coins and counterfeit coins are given a numeral indication and their corresponding delivery openings are indicated with similar numerals with an exponent "a". The sprocket tooth wheel is located in front of a diaphragm separating the legitimate coin path from the path of washers. At this point there is also provided a switch 15 in the track of the coin path, as shown in Figures 7, 8 and 9.

Figures 10 to 17 embody a modified form of my invention which is capable of less width and with a double angular path in the coin chute, thereby locating the sprocket tooth wheel in an adjacent sloping tilted path for the coins, thereby reducing the width of the device. However, the relative position of a sprocket tooth wheel may be placed anywhere in the coin path. At the top of the apparatus is supported the permanent magnet with its neutral point downward in a similar manner to Figure 1, but locked in position by a set screw and washer bridging a lug of a side wall 29. The magnet will discard a magnetic bogus coin at a point somewhere near the neutral point, as shown in Figures 2, 4, 11 and 13. The apparatus shown in these figures operates in precisely the same manner as already described in connection with the other figures, differing only in the shape of the device. The action on the respective coins will be clear from an inspection of the several figures, the several coins being given numeral characters corresponding to their character as indicated in the preceding figures. For example, 19 throughout indicates a slug or counterfeit coin of magnetic material, 27 represents a legitimate coin, 28 is a washer, and 20 is an undersized coin.

As seen in Figure 10, the magnet is supported by a lug 32, a spanning washer 31 and a set screw 30, the neutral point of the magnet being downward. In falling into the coin chute the disk is in close proximity to the lower pole of the permanent magnet and if of magnetic character is drawn to the magnet pole and rolls or slides along the same until the weakening magnetism is insufficient to hold it and, as shown in Figure 12, it is discharged from the apparatus; a non-magnetic bogus coin or a real coin, however, being unattracted by the magnet drops vertically as shown in the case of the dotted circles 27, 28, and will

descend to the sprocket tooth wheel and be delivered accordingly as it is a legitimate coin or a spurious washer into separate receptacles in a manner similar to that already described. It will be apparent, therefore, that the functional operations are identical in the form shown in Figures 10 to 17 with that in the other figures.

I have herein described my invention in its best embodiment I have hitherto been able to provide, but I would have it understood that equivalent means for accomplishing the several functions I secure, may be employed within the scope of my invention and are only limited by the terms of my appended claims.

Having thus described my invention, what I claim as new and desire to secure by Letters Patent is:

1. A coin controlling device having a pivoted sprocket toothed wheel with its teeth adapted to engage a coin traversing the coin chute and rotatable under the momentum of a coin, and two paths below the sprocket toothed wheel, one for coins and the other for washers, whereby a coin will travel in the coin path and a washer will be hooked by a tooth of the sprocket toothed wheel and be diverted to the washer path.

2. A coin controlled device comprising a gravitational path for a coin placed in the coin opening, and a discriminating rotatable toothed ejector mounted for rotation in a vertical plane and projecting into the coin path, said ejector adapted to hook and discharge washers in one path and divert legitimate coins to another path leading to a cash box.

3. A coin controlled device comprising a gravitational coin chute, a rotatable multi-toothed wheel projecting therein, the teeth adapted to rotate the wheel and be hooked on an adjacent tooth, and be carried to a discriminative branch of the coin chute.

4. A coin controlled device comprising a gravitational coin chute, a rotatable toothed wheel projecting therein adapted to hook a washer and divert to one coin channel and in the adjacent coin channel to take a legitimate coin which will glide over the wheel teeth.

In testimony whereof I affix my signature.

BENJAMIN L. FRY.
